UNITED STATES PATENT OFFICE.

GEORGE I. KING, OF DETROIT, MICHIGAN, ASSIGNOR TO AMERICAN CAR AND FOUNDRY COMPANY, OF ST. LOUIS, MISSOURI, A CORPORATION OF NEW JERSEY.

LOW-SIDE GONDOLA CAR.

SPECIFICATION forming part of Letters Patent No. 691,637, dated January 21, 1902.

Application filed June 12, 1901. Serial No. 64,244. (No model.)

To all whom it may concern:

Be it known that I, GEORGE I. KING, a citizen of the United States, residing at Detroit, in the county of Wayne and State of Michigan, have invented certain new and useful Improvements in Low-Side Gondola Cars; and I do declare the following to be a full, clear, and exact description of the invention, such as will enable others skilled in the art to which it appertains to make and use the same, reference being had to the accompanying drawings, and to the figures of reference marked thereon, which form a part of this specification.

Figure 1 is a top plan view of my improved car, part of the flooring being removed at one end to show the floor-frame underneath. Fig. 2 is a side elevational view, partly in section. Fig. 3 is a sectional view on line 3 3, Fig. 2. Fig. 4 is a sectional view on the line 4 4, Fig. 2. Fig. 5 is an elevational view of one end of the car. Fig. 6 is a detail plan view of the connection between the side and end sills. Fig. 7 is a detail perspective view of a modified form of connection between the side and end sills. Fig. 8 is a plan view showing a reinforcing cover-plate for the bolster. Fig. 9 is a sectional view on line 9 9, Fig. 8.

This invention relates to a new and useful improvement in that type of cars known as "gondola," although it is obvious that many of the details shown in the accompanying drawings and hereinafter described may be employed in other types of cars.

The objects of my present invention are to construct a car of rolled or pressed metal and to so arrange and combine the parts as to obtain the greatest strength with a comparatively small dead-weight of material used.

Another object is to simplify the construction of cars of the type mentioned, rendering the parts thereof easy of assemblage and repair.

With these objects in view the invention consists in the construction, arrangement, and combination of the several parts, all as will hereinafter be described, and afterward pointed out in the claims.

In the drawings, 1 indicates the center sill,

which is preferably composed of two channels 50 having their flanges presented outwardly.

2 indicates the body-bolster as an entirety, which consists, preferably, of two I-shaped webs extending between the center and side sills, a casting being employed between the 55 center sills, as shown. A bottom cover-plate is riveted to the bottom flanges of the I-shaped webs and the center-sill channels. I do not herein claim the construction of this body-bolster.

3 indicates end sills, which may be of any form, but which are shown as consisting of channels with their flanges presented outwardly.

4 indicates the side sills, which are preferably in the form of rolled or pressed Z-bars, the bottom flanges thereof being presented outwardly, while the top flanges are presented inwardly. These side sills are connected to the ends of the bolster-webs or bolsters, as 70 the case may be, and to the ends of the end sills by suitable connection-plates. As shown in Fig. 6, connection-plates 5 are arranged on each side of the vertical web of the Z-bar, while in Fig. 7 a single connection-plate 6 is 75 arranged outside the vertical web of the Z-bar, the bottom flange of the Z-bar being cut away to permit the connection-plate or angle to extend to the lower edge of the end sill, which end sill, as shown, extends below the 80 bottom flange of the side sill.

7 indicates a floor-sheet arranged at the end of the car, said floor-sheet being riveted to the top flanges of the end, center, and side sills and extending inwardly beyond the body- 85 bolster, to which it is also riveted and of which in Figs. 1 to 5 it forms the top cover-plate, said end sheet terminating over a splice-plate 7a. Floor-beams 8, preferably in the form of channels, are secured through suitable connection-plates to the center and side sills. There are preferably a number of these floor-beams intermediate the bolsters.

9 indicates side floor-sheets riveted to the top flanges of the center and side sills, a butt-joint being formed between the ends of these side plates and the inner edges of the end plates.

- 10 indicates the center floor-sheet, which is preferably arranged above the side and end sheets and riveted thereto and to the top flanges of the center sills. This floor-sheet 5 10 also serves as a top cover-plate for the center sill. A bottom cover-plate 11 may be riveted to the bottom flanges of the center sill, if required, or lattice-bars may be provided, as is well understood.
- 10 12 indicates the end walls of the car, preferably in the form of channels, whose bottom flanges are riveted to the end sheets 7 and to the top flanges of the center and side sills. This end wall is located a short distance from 15 the end of the car, so as to provide a platform, if desired.

The side walls of the car are in the form of sheets 13, riveted to the vertical webs of the side sills, the upper edges of said side sheets 20 having angles 14 secured thereto. These side sheets serve to carry a portion of the load, and in this capacity act as plate-girders, the top angles being placed in compression and serving as compression-flanges for the plate-girder side walls, while the side sills serve as 25 tension-flanges therefor.

In Figs. 8 and 9 I have shown the central floor-sheet as being arranged under the side and end sheets and in this manner provide a 30 space between the end floor-sheets and the body-bolsters for the introduction of reinforcing cover-plates 15, which are arranged above the bolsters.

I am aware that minor changes may be made 35 in the construction and arrangement and combination of the several parts of my invention without departing from the nature and principle of the same.

Having thus described my invention, what 40 I claim as new, and desire to secure by Letters Patent, is—

- 45 1. In a car, the combination with end and side sills, of center sills, body-bolsters, floor-plates, serving as cover-plates for the center sill and body-bolsters, and reinforcing-plates for the body-bolsters, said plates being arranged under the floor-plates, and above the bolsters, substantially as described.
2. In a car, the combination with center

and end sills, of Z-shaped side sills, floor- 50 beams extending from the side to the center sills, floor-plates riveted to the top flanges of said parts, and side walls in the form of plate-girder webs which are secured to the vertical webs of the side sills, substantially 55 as described.

3. In a car, the combination with center and end sills, of Z-shaped side sills, body-bolsters, floor-sheets riveted to the top flanges of said parts and forming cover-plates for the 60 body-bolsters and center sill, end walls, and side walls, said side walls being provided with compression-flanges along their upper edges and being secured to the vertical webs of the side sills, which serve as tension-flanges, said 65 side walls in conjunction with said flanges acting as plate-girders and assisting in carrying the load, substantially as described.

4. In a car, the combination with end, center, and side sills, said side sills being Z- 70 shaped with their bottom flanges presented outwardly and their top flanges presented inwardly, body-bolsters, floor-beams intermediate the body-bolsters and attached to the center and side sills, end floor-sheets 7, side 75 floor-sheets 9, and a center floor-sheet 10, substantially as described.

5. In a car, the combination with end, center, and side sills, said side sills being Z-shaped with their bottom flanges presented 80 outwardly and their top flanges presented inwardly, body-bolsters, floor-beams intermediate the body-bolsters and attached to the center and side sills, end floor-sheets 7, side 85 floor-sheets 9, a center floor-sheet 10, end 90 walls, and side walls riveted to the vertical webs of the side sills, and being provided with angles at their upper edges, said side walls serving in conjunction with the angles and side sills as plate-girders to carry a portion of the load, substantially as described.

In testimony whereof I affix my signature in presence of two witnesses.

GEORGE I. KING.
